CUFF LINK

Albert Joseph Rowan, Pawtuxet, R. I., assignor
to Taunton Pearl Works, a corporation of
Massachusetts

Application March 15, 1945, Serial No. 582,859

4 Claims. (Cl. 24—97)

1

This invention relates to a cuff link of the type in which one of the heads is movable for easier insertion through the buttonhole of a cuff after which the head may be moved so that the link can not return through the buttonhole to become dislodged from position in the cuff.

In the use of cuff links of the type here referred to, considerable wear occurs from movement of the cuff link head from one position to another and when excessive wear occurs the link head will not maintain itself in the definite position in which it is desired the same shall be located for insertion into the buttonhole of the cuff or in a position to block removal from the buttonhole of the cuff.

One of the objects of this invention is to provide the mounting for a movable head so that the parts which undergo wear may be formed of harder material.

Another object of this invention is to provide a pivoting member and locking rib of the same piece of material which may be formed harder than the remaining material of the head if desired.

Another object of this invention is to provide a simple, efficient, and strong means of attaching the shank of the cuff link to the fixed head.

With these and other objects in view, the invention consists of certain novel features of construction, as will be more fully described and particularly pointed out in the appended claims.

In the accompanying drawings:

Fig. 1 is a side elevation of the cuff link showing in dotted lines one of the heads moved into the position for insertion into the buttonhole of a cuff;

Fig. 2 is a view at right angles to the showing in Fig. 1 and with the fixed head in section;

Fig. 3 is a perspective view of the movable head with a mounting member removed;

Fig. 4 is a perspective view of the mounting member alone;

Fig. 5 is a sectional view on line 5—5 of Fig. 1;

Fig. 6 is a view of one of the arms looking at the inner surface thereof;

Fig. 7 is a perspective view of the fixed head;

Fig. 8 is a perspective view of the collar which when attached to the fixed head receives the shank.

In proceeding with this invention I provide a shank formed of spaced arms, these arms being brought together and secured to a fixed head at one end while the arms are spaced and pivotally mount a movable head at the other end, the head being so arranged that it may swing between the

5 arms in pivotal movement. In order to hold the movable head in certain desired positions, I have formed cruxiform grooves in the arms and have provided ribs on the head so as to lodge in one or the other of the cruxiform grooves and thus be retained in position, the arms are of sufficient resiliency so that they will spread apart while the rib is moving from one position to another and will move toward each other when the groove 10 aligns with the rib to lock the head in position.

With reference to the drawings 10 designates generally the shank, 11 the fixed head, and 12 the movable head.

The shank 10 comprises two identical arms 14 having opposed straight portions 15, inclined portions 16 and anchor portions 17. These anchor portions are in contiguous relation, as shown in Fig. 2, and are fixedly secured to the head 11.

The head 11 consists of a disc-like member 18 flanged as at 19 for the reception of an ornament 20. An opening 21 is provided centrally of this head with marginal walls 22 extending upwardly at an angle of 45°. A collar, designated generally 23 and consisting of side walls 24 forming an opening 25 of the size and shape to snugly fit the anchor portion 17 of the shank, has its walls flared outwardly as at 26 to lie along the inclined portion 22 of the head. This collar is assembled with the head and the anchor portion 17 are inserted in the collar and these three parts all soldered together as at 27 and 28 so as to firmly fix the head and shank together.

At the end portion 30 of the straight portion 15 of each of the shanks, a cruxiform groove is 35 formed by reason of a groove 31 extending longitudinally of the arm and a groove 32 extending laterally of the arm while an opening 33 is provided at the point of crossing through the arm which opening is generally circular in shape.

The head 12 has an opening 35 extending through it in the shape best shown in Fig. 3. This opening, however, is for the reception of a member 36 shown in perspective in Fig. 4 which consists of a bar 37 with trunnions 38 extending 45 from either end. This bar 37 is placed in the opening 35 with its edges in the square notches 39 having a fit sufficiently snug so that the bar will not move in the head. The end portions of the bar 37 protrude beyond the sides of the head 50 12 as shown in Fig. 5 and provide ribs 40 extending longitudinally of the head. These ribs are chisel shape and may lodge in either the groove 31 or the groove 32 which are also V-shape to fit the ribs while the trunnions extend into the openings 33 to pivotally mount the head between

the arms. As the head is moved from the position shown in full lines in Fig. 1 about its pivotal mounting the ribs act as a cam to force the arms apart as they are moved to a new location and as soon as the ribs align with the slots 31 the arms will move toward each other so that the ribs will enter these slots and maintain the head in the position shown in dotted lines in Fig. 1.

By the use of a separate member 36, such as shown in Fig. 4, this member may be made of harder material than the head to better withstand the wear caused by its camming action to spread the arms apart as the head is moved from one position to another. Should this part become worn it may be driven from the head and a new part substituted.

I claim:

1. A cuff link comprising a pair of heads with a shank connecting said heads, said shank comprising a pair of spaced arms, one of said heads being pivotally mounted in said arms and means to retain said head in position in a line with said arms or in a position at right angles thereto, comprising cruxiform grooves in one of said arms and a flat bar with V-shaped ends having trunnions protruding beyond said V-shaped ends inserted in said head to enter either of the grooves in one direction or at right angles thereto, said bar being of stock harder than said head.

2. A cuff link as set forth in claim 1 wherein

both arms are provided with said cruxiform grooves and ribs are provided on either side of said head to engage said grooves.

3. A cuff link as set forth in claim 1 wherein said arms are resilient and are flexed apart as movement occurs of said head from one position to the other.

4. A cuff link as set forth in claim 1 wherein said pivotal mounting of the head in said arms is by means of said bar extending through said head providing trunnions either side thereof.

ALBERT JOSEPH ROWAN.
